UNITED STATES PATENT OFFICE.

JOHN D. HESSLER, OF VILLA GROVE, ILLINOIS.

LOCK.

1,307,971.

Specification of Letters Patent. Patented June 24, 1919.

Application filed December 29, 1917. Serial No. 209,566.

To all whom it may concern:

Be it known that I, JOHN D. HESSLER, a citizen of the United States, residing at Villa Grove, in the county of Douglas and 5 State of Illinois, have invented new and useful Improvements in Locks, of which the following is a specification.

This invention comprehends improvements in an automatic lock primarily intended for 10 the locking of doors of toilet rooms upon railway cars when the train is approaching a station and automatically effecting the unlocking action of the door when the train is leaving a station.

15 The primary object of the invention is the provision of a device of the above stated character which is simple in construction, durable and efficient in use, and one wherein the operation thereof is controllable from 20 the trap doors of a railway car, but while the invention is particularly adaptable for railway cars, it will be evident that the same may be employed on any type of vehicle found desirable and convenient for use.

25 With the above and other objects in view, the invention consists in the novel features, details of construction and combination of parts which will hereinafter be more fully set forth, illustrated in the accompanying 30 drawings and pointed out in the appended claims.

In the drawings:

Figure 1 is a diagrammatic plan view; 35 Fig. 2 is a longitudinal sectional view; Fig. 3 is a transverse sectional view; and Figs. 4 and 5 are detail views of the lock construction.

Referring more particularly to the accompanying drawings, wherein like characters 40 of reference refer to corresponding parts in the several views, 5 denotes the flooring of a passenger coach provided with the usual toilet rooms 6, vestibules 7 and trap doors 8 swingingly positioned in the vestibules 45 for vertical movement.

Secured to the under surface of the car flooring 5 and depending therefrom are hangers 9 in which are journaled shafts 10 disposed lengthwise of the flooring and in 50 spaced parallelism one to the other, and for the sake of clearness these shafts will be hereinafter referred to as main operating shafts. The trap doors hereinbefore referred to, constitute four in number and a 55 pair of each of the doors is locked in each of the vestibules at opposite ends of the

cars and the chief characteristic of the invention resides in a novel means for operatively connecting the main operating shafts with these trap doors, whereby as the train 60 is approaching a station the swinging of the said doors to a vertical position will lock the doors 11 leading into each of the toilet rooms 6, and obviously when the train is leaving a station the swinging of the trap 65 doors to assume a horizontal position by the train crew will tend to unlock the doors 11 in order that these rooms may be accessible to the public.

In carrying out these objects, use is made 70 of a bracket arm 12 having one end rigidly connected to the bottom edge of each gate or trap door 8 and depending therefrom, while keyed or otherwise suitably connected to the opposite ends of the main operating 75 shaft 10 and projecting at right angles with respect to the link 12, is a shaft operating crank arm 13. Suitably supported on the bottom of the floor 5 at a point between the main operating shaft and trap door, is a 80 pulley 14 over which is trained a flexible connection 15 connected at one end with the free end of the bracket arm 12 and at its opposite end with the shaft operating crank arm 13. Manifestly, when the gates 85 or trap doors 8 are swung in a vertical plane, a pull will be exerted on the flexible connection 15 and which in turn will rock the main operating shaft 10 and pull the same against the tension of the spring 16. The function 90 accomplished by this operation will cause the keeper plate 17 to slide over the latch bolt 18 and accomplish the locking action of the door 11 to parties in the train. The lock operating mechanism comprises an auxiliary shaft 19 rotatably journaled in bearings 20 and arranged vertically with respect to the car floor. Carried by the main operating shaft 10 and projecting in an outward lateral direction is an arm 21 universally connected with a second arm 22 on the auxiliary shaft 19, by the link 23. That is to say, by this form of construction and upon the rocking of the main operating shaft 10, through the medium of the link 105 23, will rotate the auxiliary shaft 19 in its bearing 20, and this action will in turn rotate the pinion 24 keyed on the upper end of the auxiliary shaft 19 and mounted vertically in the bearings 25 of the casing 26. 110 In the inturned flanged guides 27 of said plate is slidably mounted the keeper plate

17, and due to the rotation of the pinion 24 will cause the same to mesh with the rack 17' on the inner face of the keeper plate 17, and move the latter over and into obstructing relation with respect to the latch bolt 18, preventing the entrance to the toilet rooms while the train is approaching or at a stand-still at stations. At this point I am desirous of stating that parties within the 10 toilet rooms are privileged in leaving the same at any time, due to the fact that the keeper bolt 18 may be unlocked from the keeper plate through the provision of a knob 28.

15 Again referring to the spring 16, the same has connection at one end to one of the side walls of the car, as denoted by the character 29, while the opposite end of the spring is connected with an arm 30 keyed or otherwise 20 suitably secured to the main operating shaft 10, and the purpose of this spring is to automatically rock the main operating shaft 10 when the gates are lowered to a horizontal position, causing a reverse rotation 25 of the pin 24, and a reverse sliding movement of the keeper plate 17, whereby the door 11 is in a released or unlocked position.

From the foregoing description, taken in 30 connection with the accompanying drawings, the advantages of construction and the method of operation will be readily apparent to those skilled in the art to which the invention relates, and while I have described the principles of operation of the 35 invention, together with the device which I now consider to be the best embodiment thereof, I desire to have it understood that the device shown is merely illustrative and 40 that such changes may be made when desired as are within the scope of the appended claims.

What is claimed as new, is:—

1. The combination with a vehicle, doors 45 located interiorly of the vehicle, swinging members arranged exteriorly of the vehicle, door locking mechanism, means for connecting the door locking mechanism with the swinging members for effecting the locking 50 action of the doors upon the swinging of the members in one direction, and rotatable means for automatically throwing the door locking mechanism to a released position upon the lifting of the swinging members in an opposite direction.

2. An automatic locking device comprising in combination with a plurality of swinging members, a main operating shaft, a connection between the main operating 60 shaft and each of said swinging members, and means operatively connected with the main operating shaft for locking the doors upon movement of the members in one di-

rection and releasing the lock when the swinging members are moved in the opposite 65 direction.

3. The combination with a vehicle, doors therefor, a lock for each door and means for operating said lock, said means comprising an operating shaft, an auxiliary rotatable 70 shaft having connection with the operating shaft, a slidable member, rotatable means carried by the auxiliary shaft for moving the slidable member.

4. In combination with a vehicle, doors 75 therefor, a plurality of swinging members arranged at the opposite ends of the vehicle, a main operating shaft journaled beneath the vehicle, a flexible connection connecting the main operating shaft with each 80 swinging member, an auxiliary shaft, a connection between the main operating shaft and the auxiliary shaft for imparting to the latter a rotary movement upon the operation of the swinging members in one direction, a locking member, and means carried by the auxiliary shaft and coöperating with the operating member for operating the locking member.

5. A door locking mechanism for vehicles 90 comprising a main operating shaft journaled lengthwise of the vehicle for oscillating movement, manually operating means having connection with the main operating shafts for moving the same in one direction, an auxiliary shaft journaled in the flooring of the vehicle and disposed at an angle with respect to the main operating shaft, a connection between the main operating shaft and the auxiliary operating shaft 95 for imparting to the latter rotary movement, a keeper plate, and means on the auxiliary shaft and coöperating with the keeper plate for imparting to the latter a sliding movement.

6. A door locking mechanism for vehicles comprising a main operating shaft journaled lengthwise of the vehicle for oscillating movement, manually operating means having connection with the main operating shafts for moving the same in one direction, an auxiliary shaft journaled in the flooring of the vehicle and disposed at an angle with respect to the main operating shaft, a connection between the main operating shaft and the auxiliary operating shaft for imparting to the latter rotary movement, a keeper plate, means on the auxiliary shaft and coöperating with the keeper plate for imparting to the latter a sliding movement, and a spring for throwing the shaft in the opposite direction.

In testimony whereof I affix my signature.

JOHN D. HESSLER.
